(57) **CLAIM**

The ornamental design for a crane for an automated warehousing system, as shown and described.

DESCRIPTION

FIG. 1 is a front perspective view of our design for a crane for an automated warehousing system;

FIG. 2 is a rear perspective view thereof;

FIG. 3 is a front view thereof;

FIG. 4 is a rear view thereof;

FIG. 5 is an enlarged top plan view thereof;

FIG. 6 is an enlarged bottom plan view thereof;

FIG. 7 is a right side view thereof;

FIG. 8 is a left side view thereof;

FIG. 9 is an enlarged view of the portion indicated by line 9—9 in FIG. 1;

FIG. 10 is an enlarged view of the portion indicated by line 10—10 FIG. 1;

FIG. 11 is an enlarged view of the portion indicated by line 11—11 FIG. 2;

FIG. 12 is an enlarged view of the portion indicated by line 12—12 FIG. 2;

FIG. 13 is an enlarged view of the portion indicated by line 13—13 FIG. 3;

FIG. 14 is an enlarged view of the portion indicated by line 14—14 FIG. 3;

FIG. 15 is an enlarged view of the portion indicated by line 15—15 FIG. 4;

FIG. 16 is an enlarged view of the portion indicated by line 16—16 FIG. 4;

FIG. 17 is an enlarged view of the portion indicated by line 17—17 FIG. 7;

FIG. 18 is an enlarged view of the portion indicated by line 18—18 FIG. 7;

FIG. 19 is an enlarged view of the portion indicated line 19—19 FIG. 8; and,

FIG. 20 is an enlarged view of the portion indicated line 20—20 FIG. 8.
